US0D1028820S

(12) United States Design Patent (10) Patent No.: US D1,028,820 S
(45) Date of Patent: * May 28, 2024

(54) MODULAR WALL MOUNT FOR A VEHICLE

(71) Applicant: Adventure Wagon LLC, Tualatin, OR (US)

(72) Inventor: Chad Smith, Portland, OR (US)

(73) Assignee: Adventure Wagon LLC, Tualatin, OR (US)

() Term: 15 Years

(21) Appl. No.: 29/809,913

(22) Filed: Sep. 30, 2021

(51) LOC (14) Cl. 12-16

(52) U.S. Cl.

USPC D12/406

(57) CLAIM

The ornamental design for a modular wall mount for a vehicle, as shown and described.

DESCRIPTION

FIG. 1 is a top, front perspective view of a modular wall mount for a vehicle in accordance with a first embodiment of my new design;

FIG. 2 is a bottom, rear perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof;

FIG. 9 is a top, front perspective view of a modular wall mount for a vehicle in accordance with a second embodiment of my new design;

FIG. 10 is a bottom, rear perspective view thereof;

FIG. 11 is a front elevation view thereof;

FIG. 12 is a rear elevation view thereof;

FIG. 13 is a right elevation view thereof;

FIG. 14 is a left elevation view thereof;

FIG. 15 is an enlarged top plan view thereof; and,

FIG. 16 is an enlarged bottom plan view thereof.
